UNITED STATES PATENT OFFICE.

D. CURTIS STANION, OF SANTA CRUZ, CALIFORNIA.

CARRIER.

1,111,927.

Specification of Letters Patent. Patented Sept. 29, 1914.

Application filed October 27, 1913. Serial No. 797,619.

To all whom it may concern:

Be it known that I, D. CURTIS STANION, a citizen of the United States, residing at Santa Cruz, in the county of Santa Cruz and State of California, have invented certain new and useful Improvements in Carriers, of which the following is a specification, reference being had to the accompanying drawings.

10 This invention relates to new and useful improvements in carriers and more particularly to a combined basket and cradle the object of the invention being to provide a device of the above character which is especially adapted for use in supporting and carrying infants and when set up, can be readily used as a sleeping cradle.

Another object of the invention is to provide a device of this character which will 20 possess advantages in points of efficiency and durability, is inexpensive of manufacture and at the same time is simple in construction and operation.

With the above and other objects in view, 25 this invention consists in the novel features of construction and the combination and arrangement of parts to be hereinafter more fully described, pointed out in the claims and shown in the accompanying drawings, 30 in which—

Figure 1 is a top plan view of a device constructed in accordance with my invention; Fig. 2 is a side elevation; Fig. 3 is a fragmental side elevation; Fig. 4 is a transverse sectional view taken through the oval portion of the side member; Fig. 5 is a similar view taken through the circular portion of the side member.

In carrying out my invention, I provide 40 a frame indicated by the numeral 1 and which is preferably constructed of heavy wire or rods integrally connected to form the longitudinal side members 2 and the end members 3. Suspended from the side pieces 45 2 and the transverse end pieces 3 is the supporting body 4 which is preferably formed of canvas or any other like material of suitable weight, the upper edge of which is lapped over the frame 1 and secured by 50 stitching, as shown at 5, any other suitable means being employed, if desired.

In carrying the body or basket from place to place, or supporting the same in spaced relation with the floor, I provide the handle 55 members 6 which are preferably U-shaped in

construction and provided at their ends with the eyes 7, said eyes being preferably oval shaped in design, as clearly illustrated in Fig. 4. The eyes 7 are slidably and rotatably mounted within the reduced portions 8 of the longitudinal side members 2. The reduced portions 8, as illustrated in the drawings, are substantially circular in cross section at one end thereof, while the other end thereof is preferably oval in shape to conform to the shape of the eyes. It will be noted from the drawings that the intermediate portions of the U-shaped members 6 are to be used as handles when conveying the basket from place to place and when it is desired to use the same as a cradle, these members will form the supporting legs which suspend the body above the floor or other surface upon which the same is resting.

It will be readily understood from the above description taken in connection with the accompanying drawings that in using the device as a basket for conveying an infant from place to place, the eyes 7 are moved laterally upon the side portions 2 until they are arranged at the circular end of the reduced portions 8, thus permitting the U-shaped members to be swung upwardly and suspended in any desirable position above the body of the basket. When it is desired to use the device as a cradle, the handles are swung downwardly to a vertical position below the body and the eyes 7 moved longitudinally upon the side members 2 until said eyes are engaged over the oval shaped portions 9, thus preventing any rotary movement of the eyes upon the side portions which will securely hold the U-shaped members in an upright position.

From the above description taken in connection with the accompanying drawings, it will be readily apparent that I have provided a simple and durable carrier which is especially adapted for use in conveying infants from one place to another or the same can be readily used as a cradle, when desired. It will also be apparent that the device is extremely simple in construction and can be manufactured at a comparatively low cost.

While I have shown and described the preferred form of my invention, it will be obvious that various changes in the details of construction and in the proportions may be resorted to for successfully carrying my

invention into practice without sacrificing any of the novel features or departing from the scope of the appended claims.

It will be readily understood that the eyes 5 7 of the handle members 6 may be electrically welded to the frame if so desired or a lock may be electrically welded upon the frame bar, if so desired. It will also be apparent that the oval portions which are arranged adjacent the reduced portions 8 may 10 be eliminated at one end of the handle members, as clearly illustrated in the drawings or they may be used at both ends, if desired.

What I claim is:—

15 1. A device of the class described including a substantially rectangular frame, a flexible body having its upper edge secured to the frame, U-shaped members having certain of their ends formed oval in shape and 20 rotatably mounted upon the side portions of the frame, whereby they may be disposed above or beneath the frame, and means co-acting with said oval-shaped ends for retaining said U-shaped members against 25 movement, when disposed beneath the frame.

2. A device of the class described including a substantially rectangular frame, a flexible body suspended from the frame, 30 the side members of said frame being provided with reduced portions, said reduced

portions being circular in form at one end and oval in form at the other end, U-shaped members having oval shaped eyes formed on certain of their ends and mounted 35 within said reduced portions, said eyes being arranged upon the circular portions when moving said U-shaped members and said eyes being arranged upon the oval portions to retain the U-shaped members against 40 movement.

3. A device of the class described including a substantially rectangular frame, a flexible body suspended therefrom, the side members of said frame having reduced portions, said reduced portions being provided with a circular and an oval portion, U-shaped members having oval shaped eyes formed at the ends thereof, which are mounted upon the reduced portions, said 50 eyes being arranged upon the circular portion when actuating the handle and adapted to be arranged upon the oval portion to retain the U-shaped members in their operative position. 55

In testimony whereof I hereunto affix my signature in the presence of witnesses.

D. CURTIS STANION.
